CLAIM

The ornamental design for a garment, as shown and described.

DESCRIPTION

FIG. 1 is a front view of a garment lying flat.

FIG. 2 is a rear view thereof.

FIG. 3 is a top view thereof.

FIG. 4 is a bottom view thereof.

FIG. 5 is a right side view of a garment lying flat on its side; and,

FIG. 6 is a left side view of a garment lying flat on its side. The short broken lines are shown for the purpose of illustrating environmental subject matter that forms no part of the claim. The long broken lines represent seams that form part of the claim.

1 Claim, 4 Drawing Sheets
